UNITED STATES PATENT OFFICE.

DANIEL M. NIXON, OF DANVILLE, ILLINOIS.

IMPROVED HARNESS-BUCKLE.

Specification forming part of Letters Patent No. 42,787, dated May 17, 1864.

To all whom it may concern:

Be it known that I, DANIEL M. NIXON, of the town of Danville, in the county of Vermillion, State of Illinois, have invented a new and Useful Harness-Buckle; and I do hereby declare that the following is a full and exact description thereof, reference being had to the accompanying drawings, forming a part of this specification, and to the letters of reference marked thereon.

In the drawings, figure I is a plan view of the buckle with portion of the hame-tug and trace attached. Fig. II is a section of Fig. I through the red line *x x*; Figs. III and IV, views of the tongue of the buckle.

In all of these figures the same letter is used to designate the same parts.

To enable others skilled in the art to make and use my invention, I give the following description of its construction and operation.

A A represents the frame of the buckle; B B, the tongue; B' B', the point of B B turned to enter the holes *h h* in the trace *e e*; D, the cross bar near the center, and passing from one side of the frame to the other; *a a*, the front bar; *a' a'*, the back bar; *b*, the loop for breeching; *c c*, loops for pad and belly-band; *d d*, hame-tug; *e e*, trace; *g g*, groove in end of tongue B and fitting on cross-bar D; *h h*, holes for the reception of the point B' of the tongue.

It will be seen that I make a certain portion of the frame of my buckle—say, from *q* to *q*, Fig. II—plain or flat, and curve up the two ends. The object of this is to give an even surface to press upon the side of the animal. This is an object of much importance in heavy draft, where the pad and belly-band are attached to the buckle by loops, such as *c c*. The curved ends with the end bars, *a* and *a'*, form loops for receiving the end of the trace. The groove *g* of the tongue B is placed upon the cross-bar D, and thus held by the end of the hame-tug, which is passed around and firmly secured upon them both by stitching, as is usually done, a hole having been previously made

therein for the passage of the point B' through the upper or outer fold of the hame-tug. By this arrangement the tongue is as firmly held upon the cross-bar, as if it entirely surrounded it, and the point B', coming in contact with the end bar, *a*, is firmly braced or stayed by it, thereby preventing the possibility of throwing the groove out of place. If the point B' were, as in some harness-buckles, within the bar *a*, having then no support but its own strength, it would be not only much more liable to be broken off when great strain should be put upon the trace, but also to be drawn back, and thus throw the groove *g* from its place upon the cross-bar; and, as this grooved end of the tongue is as wide as the buckle—that is, extends from side to side—it is pressed upon by the entire width of the trace, which thus becomes an additional means of holding it in place. In the construction of my buckle I put the cross-bar D about half an inch forward of the center of the frame in buckles of the size shown in the drawings and a greater or less distance in proportion to the size of the buckle. By this construction I get a stronger leverage for holding the end bar, *a*, against the point B', for when the trace is drawn upon strongly it rises up under the end bar, *a*, and the more the draft, the more this end will tend to raise up and throw the anterior bar *a* against the point B'.

Ordinary leather loops are applied (not shown in the drawings) for holding the free end of the trace in its place upon the hame-tug.

Having thus described my invention, what I claim, and desire to secure by Letters Patent of the United States, is—

The frame A, with its curved end and bars *a a'* and cross-bar D, in combination with the tongue B, with its grooved end *g* and point B', constructed and operating as described.

DANIEL M. NIXON.
